NAILING DEVICE AND NAILS INSERTED
THEREBY

Max Vogel, Bridgeport, Conn.

Application June 13, 1944, Serial No. 541,199

15 Claims. (Cl. 1—46)

1

The present invention relates to nailing, particularly to an improved nail structure and to a magazine type nailing device therefor, wherein a quantity of the nails are carried and are adapted to be successively fed and individually driven through the operation of the device.

It is an object of the invention to provide a nail structure, preferably of sheet metal, and comprising a prong part and a head part, both disposed in co-planar relation in their form as 10 contained in the nailing device prior to being driven into the material to be nailed, the nail structure having a bending line between its two parts, whereby, following the driving of the prong part into the material, the head part is adapted through the driving operation to be bent at a right angle to the driven prong part, thus providing a flat head engaged upon the surface of the material.

It is a further object to provide such nail structure which will permit a relatively large number of the nails to be adhesively connected in a strip or block with their side surfaces contacting each other and their top end edge surfaces exposed, and whereby the foremost nail in the strip or block may be disengaged therefrom and driven through pressure applied against the top edge thereof, such pressure being exerted by a driver which simultaneously drives the prong part of the nail into the material and bends the head part.

A further object is to provide a nail structure wherein shoulder means is provided at the lower edge of the head part, contiguous to the top of the prong part, and substantially in line with the bending line between the head and prong parts for the purpose of limiting the penetration of the material to the prong part, so that the head part is prevented from entering the material.

A further object is to provide a nailing device including guide means for the nail being driven, operative during penetration of the prong part into the material to maintain the head part in unbent relation and in the vertical plane of the prong part, and releasing means, operative at the completion of the driving of the prong part into the material for permitting the driving force of the driver to exert a component force upon the head part to bend it at right angles to the prong part and into contact with the surface of the material.

A further object is to provide a nailing device having abutment means for cooperation with the shoulder means of the nail, for the purpose of effectually limiting the insertion of the prong part into the material.

2

Another object is to provide driving means adapted during the driving operation to create a tipping moment in the head part of the nail to cause it to bend at a right angle to the prong part along the bending line while remaining flat, so that the bent head of the driven nail engages in flat relation upon the surface of the material.

With the above and other objects in view embodiments of the invention are shown in the accompanying drawings, and these embodiments will be hereinafter more fully described with reference thereto, and the invention will be finally pointed out in the claims.

In the drawings:

15 Fig. 1 is a perspective view of a nail, according to the invention, in its form before being driven by means of the nailing device of the invention.

20 Fig. 2 is a cross-sectional view of material to be nailed, showing the nail in front view, as driven into the material and before bending of the head part.

25 Fig. 3 is a longitudinal sectional view, showing the driven nail in the relation illustrated in Fig. 2, in side edge elevation.

Fig. 4 is a similar view, showing the driven nail with the head part bent into flat engagement with the upper surface of the nailed material.

30 Fig. 5 is a side elevation of the forward end portion of the nailing device of the invention, a strip or block of nails being shown therein.

Fig. 6 is a front elevation.

Fig. 7 is a horizontal sectional view, taken along the line 1—1 of Fig. 5.

35 Fig. 8 is a vertical sectional view, showing the driver part of the device depressed to the point where the prong part of the nail is driven into the material and prior to the bending of the head part.

40 Fig. 9 is a vertical sectional view, showing the driver in its completely depressed position with the head part of the nail bent into flat engagement with the surface of the nailed material.

45 Fig. 10 is a perspective view of a modified form of nail.

Fig. 11 is a cross-sectional view of material to be nailed, showing the nail of Fig. 10 in side edge elevation, as driven into the material and before bending of the head part.

50 Fig. 12 is a similar view, showing the driven nail with the head part bent into flat engagement with the upper surface of the nailed material and folded upon itself.

55 Fig. 13 is a fragmentary vertical sectional

view, showing the head part partially bent and folded by the nailing device driver.

Fig. 14 is a similar view, showing the nail head completely bent and folded by the driver.

Fig. 15 is a perspective view of another modified form of nail.

Fig. 16 is a cross-sectional view of the material to be nailed showing the nail of Fig. 15 in side edge elevation, as driven into the material and before bending of the head part.

Fig. 17 is a similar view, showing the driven nail with the head part bent into flat engagement with the upper surface of the nailed material and folded upon itself.

Fig. 18 is a fragmentary vertical sectional view, showing the head part partially bent and folded by the nailing device driver.

Fig. 19 is a similar view, showing the nail head completely bent and folded by the driver.

Fig. 20 is a front elevation of another modified form of nail, and showing in cross-sectional view the abutment projections of the nailing device as engaged therewith.

Fig. 21 is a similar view of a further modified form of nail.

Fig. 22 is a similar view of still another modified form of nail.

Fig. 23 is a fragmentary vertical sectional view of a modified form of driver, shown in raised position.

Similar reference characters indicate corresponding parts throughout the several figures of the drawings.

Referring to the drawings, the nail, according to the exemplary illustrated embodiment of the invention shown in Figs. 1 to 4, is formed of flat sheet metal or similar material, and comprises a head part 10 of octagonal form and a pointed prong part 11 of substantially V-form, the upper wide end of the prong part corresponding in width to the lower horizontal edge of the head part, so that upwardly inclined abutment shoulders 12-12 are provided at the base of the head part contiguous to the upper end of the prong part. The bending line between the head part and the prong part is substantially at the upper end of the prong part and is preferably defined by a grooved depression 13 provided in the upper end of the prong part with its upper edge substantially in line with the lower ends of the shoulders 12-12, so that the bending between the prong part and the head part takes place in the upper end of the prong part. This arrangement is especially adapted for cooperation with abutment means provided in the nailing device, presently to be more fully described, whereby such abutment means engages the shoulders 12-12 to limit the penetration of the prong into the material and therefore allows the head to bend into engagement with the surface of the material, at the same time disengaging the shoulders from the abutment means and bringing the flat surface of the head into flat contact with the surface of the material.

The nailing device, for cooperation with the nail as shown in Figs. 1 to 4, comprises a magazine 14 having a horizontally extending passage 15 therethrough corresponding in cross-sectional shape to the outline of the nail and adapted to receive a strip or block of the nails adhesively connected together. The magazine is conveniently formed of two opposed identical half sections having vertically extending driver supporting parts 16 at their forward ends, the two half sections being secured together by transverse

75 screws or bolts 17. At the forward end of the magazine a bearing plate 18 is set into a recess 19 with its forward surface in a vertical plane in flush relation with the vertical forward surface of the driver supporting parts 16, being provided with a nail receiving opening 20 conforming to and registering with the magazine passage 15.

The vertical driver passage is conveniently 10 formed by spacer strips 21-21, disposed in spaced parallel relation to each other upon the forward end of the frame adjacent each of its vertical side edges, the lateral spacing of these strips corresponding to the width of the nail head and the thickness of the strips corresponding to the thickness of the sheet metal material of which the nails are formed, there being sufficient clearance to allow driving movement of the nail in the space provided by the strips. Upon 15 the strips 21 there are secured by screws 22^a retaining strips 22 somewhat wider along their major length than the strips 21, having their outer edges flush with the outer edges of the strips 21 and their inner edges projected inwardly with 20 respect to the inner edges of the strips 21, so that these strips 22 provide retaining flanges projecting over the margins of the nail heads. The space between these retaining flanges is slightly greater than the width of the upper wide end 25 of the prong part of the nail, so that while they confine the head part of the nail at each side, they do not contact the prong part. The retaining flanges terminate in spaced relation above the lower end of the driving passage a distance corresponding to the height of the head 30 part of the nail, so that a free space 23 is provided forwardly of the head part in which the head part of the nail may bend forwardly, after the prong part is driven into the material being 35 nailed.

The bearing plate 18 is provided upon its front 40 face adjacent its lower end and adjacent its side edges with forwardly projecting abutment projections 24-24 disposed in direct vertical line with the angular shoulders 12-12 of the nail being driven, the projection of these abutment portions substantially corresponding to the thickness of the sheet metal material of the nail and their lateral spacing being slightly greater than the wide upper end of the prong part of the nail 45 so that this prong part will engage between them. The upper surfaces of the abutments are inclined downwardly and inwardly, to conform to the angular shoulders 12-12, and so that as the nail is driven and its shoulders come into contact with the abutments the wedging effect of the abutments on the shoulders in cooperation with the forward free space 23, will resolve itself into a forward bending moment upon the head of 50 the nail to start its bending forwardly about the bending line 13. The inclined shape of the abutments, in cooperation with the inclined shoulders of the nail head part permit the latter to freely swing forwardly without appreciable resistance.

60 The driver comprises a driving strip 25 corresponding in thickness to the thickness of the material of the nail and engaged in the driving space between the spacer strips 21, having secured to it by means of screws 26 a driving member 27, of T-shape in cross-section, having its narrow portion slideably disposed between the strips 22 and its wide forward portion disposed over the forward faces of the strips 22, this wide portion being substantially the same width as the 65 head of the nail. The bottom surface of the driv-

ing member 27 is preferably flat and horizontally disposed in flush relation to the lower flat end of the driving strip 25.

The lower corners of the driving strip 25 are cut out, as at 37—37, to clear the abutment projections 24, so that the effectual driving force of the driver may be extended below the abutment projections to firmly impact the head part of the nail against the material being nailed.

As shown in Fig. 23 the driving strip 25 may have a relatively sharp fin or tooth 25^a at its rearward edge sufficiently thin so that it engages behind the edge of the nail head to insure its forward bending as the head is released from the retaining strips 22. To facilitate this action the edge of the nail head may be slightly beveled at its rearward side, as at 10^a.

To the upper end of the driving member 27 there is secured a plunger 29 slideably engaged through an apertured top plate 30 secured by screws 30^a to the upper ends of the vertical driver supporting parts 16 of the magazine, this plunger having a helical compression spring 31 engaged about it between the plate 30 and a head 32, which normally exerts upward force upon the driving member to retain it in its upper position. A shoulder 33 on the plunger is adapted to engage the top plate 29 in the depressed position of the driving member to limit its downward movement.

Within the magazine passage 15 there is slideably engaged a push shoe 34 normally pressed forwardly by means of a spring 35 to exert forward pressure upon the strip or block of nails, and adapted to be retracted for the purpose of refilling the magazine with nails by means of a handle 36.

In operation, the nails are inserted in the nailing device in the form of a strip or block wherein the individual nails are preferably adhesively connected together by a suitable adhesive substance which permits the ready separation of the foremost nail of the strip by pressure applied against an edge thereof. The foremost nail of the strip is pressed against the flange projections of the retaining strips 22 and into vertical alignment with the driving strip 25 through the forward pressure of the push shoe, and is adapted to be driven into the material to be nailed by depressing the driving strip through pressure applied to the plunger 29. During the initial driving movement the head part of the nail is supported by the retaining flanges of the strips 22 as the prong part is driven into the material, the nail being held against bending through the fact that the head part of the nail is retained by the flanges. While the pointed prong part is not retained forwardly its inherent shape is such that it will drive into the material without bending, the sharply pointed end entering the material with relatively little pressure, while the length of the prong part disposed above the material gradually increases in width as it decreases in length, so that the resistance to bending is proportionately increased with the increased resistance to penetration of the widening upper part of the prong. In practice, it is found that with this shape prong the nail will penetrate wood or other relatively hard material without bending between its ends.

The penetration of the nail is limited by engagement of the shoulders 12 with the abutment projections 24, and at this point the head part moves into the forwardly clear opening 23 out of engagement with the retaining flanges of the

strips 22. As the rearward surface of the head part of the nail is supported by the forward surface of the bearing plate 18, the downward pressure of the driver causes the head part of the nail to bend forwardly about its bending line 13, the grooved depression forming it being disposed in the forward side of the nail so that the downward pressure of the driver tends to force the head part forwardly rather than to bend or buckle it between its lower and upper ends. As soon as the head part starts to bend forwardly about the bending line its upper edge rides forwardly upon the flat lower surface of the driver and is finally pressed into flat engagement with the surface of the material being nailed, the bending of the head part causing the shoulders 12 to swing forwardly of the abutment projections 24 so that they are clear of the projections and therefore engage flatly against the surface of the material. The inward and downward inclination of the abutment projections 24 is such that upon engagement of the inclined shoulder surfaces 12 therewith a slight wedging effect takes place which resolves itself into a forward bending moment in the nail head to thereby further insure its forward bending about the bending line 13. Upon release of the driver it retracts to its upper position and another nail of the strip moves into place in the driving passage.

In Figs. 10 to 14 there is shown a modified form of nail according to the invention wherein the head part 10 is provided with V-shaped notches 38—38 in its side edges providing a weakened area constituting a bending line substantially midway between its upper and lower edges. It will be understood that instead of the notches a suitable score line may be provided in the rearward side of the head to produce a weakened bending area across its medial line. This form of the head is adapted during the driving operation to fold upon itself, as shown in Fig. 12, at the completion of the penetration of the prong part of the nail, thus providing a double thickness head. The nail is adapted to be driven in the same driving device as shown in Figs. 13 and 14, the upper edge of the head remaining in engagement with the lower end of the driving strip 25, so that the head bends forwardly in line with the notches 38 at the completion of the penetration of the prong part, the folded head being flattened against the nailed material through impact of the driver at the completion of its downward movement.

In Figs. 15 to 19 there is shown another modified form of nail according to the invention, in which the head 10 is provided with notches 39 disposed at a point near the shoulders 12 substantially one-third the height of the head. In this case the folded head projects both forwardly and rearwardly of the driven prong part. It is adapted to be driven in the same driving device, as shown in Figs. 5 to 9, the upper edge of the nail head as it is driven to its flat position moving the driving device rearwardly, as shown in Figs. 18 and 19, following the driving of the prong part, so that at the completion of the driving operation the driver is impacted against the folded head part forwardly and rearwardly of the driven prong part.

In Figs. 20 to 22 there are shown further modified forms of nails according to the invention, as well as modifications in the abutment projections 24 of the nailing device to accommodate these modified forms of nails.

In Fig. 20 the nail is shown as provided with

a pair of spaced prong parts 11^a, having inclined shoulders 12^a at each side, the inner shoulders forming an inverted V. Three abutment projections 24^a of corresponding shape are provided for engagement therewith. Grooved depressions 13^a are provided at the upper ends of the prong parts.

In Fig. 21 a pair of prong parts 11^b-11^b are provided, the outer edges of these prong parts being vertically disposed in line with the side edges of the head part and the inner edges being inclined outwardly and downwardly to a point, so that during the driving of the prongs into the material they are supported at their outer sides by the side walls of the driving channel. The shoulder 12^b between the prongs is of inverted V-shape. A correspondingly shaped single abutment projection 24^b is provided in the nailing device to engage the shoulder between the two prong parts. Grooved depressions 13^b-13^b are provided at the upper ends of the prong parts.

In Fig. 22 short prongs 40-40 are provided at each of the lower corners of the head part, and are adapted to penetrate a short distance into the material being nailed. Inverted V-shaped shoulders 12^c are provided between the short prongs 40 and the central prong 11^c. A grooved depression 13^c is provided at the upper end of the prong 11^c. The nailing device is provided with correspondingly shaped abutment projections 24^c-24^c in inwardly spaced relation to the side walls of the driving channel in order to provide passages for the short prongs 40.

The nailing device according to the invention may be incorporated in any suitable type of magazine structure having a reciprocating driver. For instance, it might be incorporated in a power-operated device, as well as in a hammer-like device. This latter type usually includes a weight movably carried in a guide channel above the driver, the relation of the weight to the handle being such that as the handle is raised the weight slides upwardly. As the handle is brought down during the hammering operation the weight is thrown against the driver causing it to drive the nail. This type of device is well-known in the art so that no further description and illustration thereof is deemed necessary, it being pointed out that according to the invention the known type of device is simply adapted to the specific nail magazine, nail driving passage, driver, and driver guide structure, as shown in Figs. 5 to 9.

I have illustrated and described preferred and satisfactory embodiments of the invention, but it will be understood that changes may be made therein, within the spirit and scope thereof, as defined in the appended claims.

Having thus described my invention what I claim and desire to secure by Letters Patent is:

1. A nail structure comprising a head part and a prong part integrally connected together, said head and prong parts in their pre-driven state being disposed in co-planar relation with their front and rear surfaces in the same plane and being entirely free of any projections beyond said surfaces, whereby the rear surface of the head and prong parts may have downward sliding engagement with the front surface of a similar contiguous nail structure disposed in a driving implement, said prong part having at least one of its side edges entirely inwardly offset from and below the side edges of said head part, and said head part having at its upper edge a driver engaging surface for driving engagement by the driver of a driving implement and having at its lower

edge an abutment shoulder forming an angular corner with said inwardly offset side edge of said prong part, the straight transverse line of said prong part coinciding with said angular corner constituting the bending line between said head and prong parts, said shoulder adapted in the co-planar relation of said head and prong parts to limit the insertion of the prong part in material being nailed to the full length of said prong part, the marginal portion of said head part between its upper edge and said shoulder being a guide portion for engagement with guide means of a driving implement said head part being bendable with respect to the fully driven prong part about said bending line into angular relation to said prong part to dispose said head part in engagement with the surface of the material being nailed.

2. A nail structure comprising a head part and a prong part integrally connected together, said head and prong parts in their pre-driven state being disposed in co-planar relation with their front and rear surfaces in the same plane and being entirely free of any projections beyond said surfaces, whereby the rear surface of the head and prong parts may have downward sliding engagement with the front surface of a similar contiguous nail structure disposed in a driving implement, said prong part having its side edges entirely inwardly offset from and below the side edges of said head part, and said head part having at its upper edge a driver engaging surface for driving engagement by the driver of a driving implement and having at its lower edge abutment shoulders extending inwardly from its side edges to form transversely opposed angular corners with the side edges of said prong part, the straight transverse line between said angular corners constituting the bending line between said head and prong parts, said shoulders adapted in the co-planar relation of said head and prong parts to limit the insertion of the prong part in material being nailed to the full length of said prong part, the marginal portions of said head part between its upper edge and said shoulders being guide portions for engagement with guide means of a driving implement said head part being bendable with respect to the fully driven prong part about said bending line into angular relation to said prong part to dispose said head part in engagement with the surface of the material being nailed.

3. A nail structure comprising a head part and a prong part integrally connected along a straight transverse bending line, said head and prong parts in their pre-driven state being disposed in co-planar relation with their front and rear surfaces in the same plane and being entirely free of any projections beyond said surfaces, whereby the rear surface of the head and prong parts may have downward sliding engagement with the front surface of a similar contiguous nail structure disposed in a driving implement, said head part having at its upper edge a driver engaging surface for driving engagement by the driver of a driving implement and having at its lower edge an abutment shoulder inclined downwardly to a point of coincidence with said transverse bending line for engagement with stop means of a driving implement and adapted in the co-planar relation of said head and prong parts to limit the insertion of the prong part in material being nailed to the full length of said prong part, the marginal portion of said head part between its upper edge and said shoulder being a guide portion for en-

gagement with guide means of a driving implement said head part being bendable with respect to the fully driven prong part about said bending line into angular relation to said prong part to dispose said head part in engagement with the surface of the material being nailed.

4. A nail structure comprising a head part and a prong part integrally connected along a straight transverse bending line, said head and prong parts in their pre-driven state being disposed in co-planar relation with their front and rear surfaces in the same plane and being entirely free of any projections beyond said surfaces, whereby the rear surface of the head and prong parts may have downward sliding engagement with the front surface of a similar contiguous nail structure disposed in a driving implement, said prong part being in the form of a single centrally disposed prong having its side edges convergingly inclined downwardly to a point and entirely inwardly offset from and below the side edges of said head part, and said head part having at its upper edge a driver engaging surface for driving engagement by the driver of a driving implement and having at its lower edge abutment shoulders at each side of said prong part adapted in the co-planar relation of said head and prong parts to limit the insertion of the prong part in material being nailed to the full length of said prong part, the marginal portions of said head part between its upper edge and said shoulders being guide portions for engagement with guide means of a driving implement said head part being bendable with respect to the fully driven prong part about said bending line into angular relation to said prong part to dispose said head part in engagement with the surface of the material being nailed.

5. A nail structure comprising a head part and a prong part integrally connected along a straight transverse bending line, said head and prong parts in their pre-driven state being disposed in co-planar relation with their front and rear surfaces in the same plane and being entirely free of any projections beyond said surfaces, whereby the rear surface of the head and prong parts may have downward sliding engagement with the front surface of a similar contiguous nail structure disposed in a driving implement, said prong part being in the form of a single centrally disposed prong having its side edges convergingly inclined downwardly to a point and entirely inwardly offset from and below the side edges of said head part, and said head part having at its upper edge a driver engaging surface for driving engagement by the driver of a driving implement and having at its lower edge abutment shoulders at each side of said prong inclined downwardly and inwardly to points of coincidence with the ends of said transverse bending line for engagement with stop means of a driving implement, and adapted in the co-planar relation of said head and prong parts to limit the insertion of the prong part in material being nailed to the full length of said prong part, the marginal portions of said head part between its upper edge and said shoulders being guide portions for engagement with guide means of a driving implement said head part being bendable with respect to the fully driven prong part about said bending line into angular relation to said prong part to dispose said head part in engagement with the surface of the material being nailed.

6. A nail structure comprising a head part and a prong part integrally connected along a trans-

verse bending line, said head and prong parts in their pre-driven state being disposed in co-planar relation, said prong part being in the form of a plurality of spaced prongs, and said head part having abutment shoulder means at its lower edge between the upper ends of said prongs adapted to limit the insertion of the prong part in material being nailed, said head part being bendable with respect to said prong part about said bending line into angular relation to said head part to dispose said head part in engagement with the surface of the material being nailed.

7. A nail structure comprising a head part and a prong part integrally connected along a transverse bending line, said head and prong parts in their pre-driven state being disposed in co-planar relation, said prong part being in the form of a centrally disposed prong having its side edges convergingly inclined downwardly to a point and substantially shorter prongs outwardly spaced therefrom at each side, and said head part having abutment shoulders at its lower edge between said central prong and said outwardly spaced shorter prongs adapted to limit the insertion of the prong part in material being nailed, said head part being bendable with respect to said prong part about said bending line into angular relation to said prong part to dispose said head part in engagement with the surface of the material being nailed.

8. A nail structure comprising a head part and a prong part integrally connected along a transverse bending line, said head and prong parts in their pre-driven state being disposed in co-planar relation, said head part having an abutment shoulder at its lower edge adapted to limit the insertion of the prong part in material being nailed, said head part being bendable with respect to said prong part about said bending line to dispose said head part in engagement with the surface of the material being nailed, and said head part being foldable upon itself about a transverse weakened bending line intermediate its upper and lower edges.

9. A nail structure comprising a head part and a prong part integrally connected along a transverse bending line, said head and prong parts in their pre-driven state being disposed in co-planar relation, said head part having an abutment shoulder at its lower edge adapted to limit the insertion of the prong part in material being nailed, said head part being bendable with respect to said prong part about said bending line to dispose said head part in engagement with the surface of the material being nailed, and said head part being foldable upon itself about a transverse weakened bending line midway its upper and lower edges.

10. A nail structure comprising a head part and a prong part integrally connected along a transverse bending line, said head and prong parts in their pre-driven state being disposed in co-planar relation, said head part having an abutment shoulder at its lower edge adapted to limit the insertion of the prong part in material being nailed, said head part being bendable with respect to said prong part about said bending line to dispose said head part in engagement with the surface of the material being nailed, and said head part being foldable upon itself about a transverse weakened bending line intermediate its upper and lower edges, and nearer said lower edge, the head portion below said bending line

being approximately half the height of the portion above it.

11. In a nailing device, for driving and bending a nail member including an upper head part and a lower prong part disposed in co-planar relation and integrally connected along a transverse bending line, and wherein said head part has abutment shoulder means at its lower edge, nail driving passage means adapted to receive said nail for vertical driving movement therein, retaining flange means disposed at and constituting the forward side of the upper part of said passage means, said nail adapted to be engaged in said passage with its side marginal portions forwardly engaged by said retaining flange means, said retaining flange means terminating at a point spaced above the base of said passage means a distance at least equal to the height of the head part of said nail to provide at the lower part a free space for the forward bending of said head part from said passage means as it is driven downwardly in said passage below said retaining flange means, a driver engaged in said passage means for vertical driving movement therein including a lower driving surface adapted to engage the upper edge of the head part of said nail during driving of the prong part into material being nailed and a bending surface adapted to be slidably engaged by the upper edge of said head part as it is bent forwardly about its bending line in said free space and further to impact the bent head part against the surface of the material being nailed.

12. In a nailing device, for driving and bending a nail member including an upper head part and a lower prong part disposed in co-planar relation and integrally connected along a transverse bending line, and wherein said head part has abutment shoulder means at its lower edge, nail driving passage means adapted to receive said nail for vertical driving movement therein, retaining flange means constituting the forward side of said passage means and terminating at a point spaced above the base of said passage means a distance at least equal to the height of the head part of said nail to provide a free space for the forward bending of said head part from said passage means, a driver engaged in said passage means for vertical driving movement therein including a lower driving surface adapted to engage the upper edge of the head part of said nail during driving of the prong part into material being nailed and a bending surface adapted to be slidably engaged by the upper edge of said head part as it is bent forwardly about its bending line in said free space and further to impact the bent head part against the surface of the material being nailed, and abutment projection means at the lower end of said passage arranged to engage said abutment shoulder means of said nail to limit the penetration of the prong part into the material being nailed.

13. In a nailing device, for driving and bending a nail member including an upper head part and a lower prong part disposed in co-planar relation and integrally connected by a transverse bending line, and wherein said head part has abutment shoulder means at its lower edge inclined downwardly to a point coincident with said bending line, nail driving passage means adapted to receive said nail for vertical driving movement therein, retaining flange means constituting the forward side of said passage means and terminating at a point spaced above the base of said passage means a distance at least equal to the height

of the head part of said nail to provide a free space for the forward bending of said head part from said passage means, a driver engaged in said passage means for vertical driving movement therein including a lower driving surface adapted to engage the upper edge of the head part of said nail during driving of the prong part into material being nailed and a bending surface adapted to be slidably engaged by the upper edge of said head part as it is bent forwardly about its bending line in said free space and further to impact the bent head part against the surface of the material being nailed, and abutment projection means at the lower end of said passage having a downwardly inclined upper surface arranged to engage said inclined abutment shoulder means of said nail to limit the penetration of the prong part into the material being nailed.

14. In a nailing device, for driving and bending a nail member including an upper head part and a lower relatively narrower central prong part disposed in co-planar relation and integrally connected by a transverse bending line, and wherein said head part has abutment shoulders at its lower edge at each side of said prong part inclined downwardly and inwardly to points coincident with said bending line, nail driving passage means adapted to receive said nail for vertical driving movement therein, retaining flange means constituting the forward side of said passage means and terminating at a point spaced above the base of said passage means a distance at least equal to the height of the head part of said nail to provide a free space for the forward bending of said head part from said passage means, a driver engaged in said passage means for vertical driving movement therein including a lower driving surface adapted to engage the upper edge of the head part of said nail during driving of the prong part into material being nailed and a bending surface adapted to be slidably engaged by the upper edge of said head part as it is bent forwardly about its bending line in said free space and further to impact the bent head part against the surface of the material being nailed, and spaced abutment projection means at the lower end of said passage each having a downwardly and inwardly inclined upper surface arranged to engage the respective abutment shoulders of said nail at each side of said prong part to limit the penetration of the prong part into the material being nailed.

15. In a nailing device, for driving and bending a nail member including an upper head part and a lower prong part disposed in co-planar relation and integrally connected along a transverse bending line, and wherein said head part has abutment shoulder means at its lower edge, nail driving passage means adapted to receive said nail for vertical driving movement therein, retaining flange means disposed at and constituting the forward side of the upper part of said passage means, said nail adapted to be engaged in said passage with its side marginal portions forwardly engaged by said retaining flange means, said retaining flange means terminating at a point spaced above the base of said passage means a distance at least equal to the height of the head part of said nail to provide at the lower part a free space for the forward bending of said head part from said passage means as it is driven downwardly in said passage below said retaining flange means, a driver engaged in said passage means for vertical driving movement therein including a lower driving surface adapted to engage the upper edge of the head part of said nail during

13

driving of the prong part into material being nailed and a bending surface of flat form disposed at a right angle to the direction of said passage means adapted to be slidably engaged by the upper edge of said head part as it is bent forwardly about its bending line in said free space and further to impact the bent head part in flat relation against the upper surface of the material being nailed.

MAX VOGEL. 10
